UNITED STATES PATENT OFFICE.

THEODORE H. LUNDE, OF CHICAGO, ILLINOIS, ASSIGNOR TO AMERICAN INDUSTRIAL CO., OF CHICAGO, ILLINOIS, A CORPORATION OF ILLINOIS.

MUSIC-DESK HANGER FOR PIANOS.

No. 918,066.

Specification of Letters Patent. Patented April 13, 1909.

Application filed June 16, 1908. Serial No. 438,784.

To all whom it may concern:

Be it known that I, THEODORE H. LUNDE, a citizen of the United States, and a resident of Chicago, in the county of Cook and State of Illinois, have invented certain new and useful Improvements in Music-Desk Hangers for Pianos; and I do hereby declare that the following is a full, clear, and exact description thereof, reference being had to the accompanying drawings, and to the letters of reference marked thereon, which form a part of this specification.

This invention relates to improvements in music desk hangers or hinges for upright pianos, and the invention consists in the matters hereinafter set forth and more particularly pointed out in the appended claims.

Among the objects of my invention is to provide a music desk hanger or hinge for pianos which is so constructed and arranged as to permit the music desk to be swung forwardly and upwardly at its lower side, for the purpose of exposing the piano action in rear thereof for inspection, while avoiding tendency of the desk sliding inwardly toward the piano action in a manner to injure the mechanism of the action, and also to provide a hanger for this purpose which is so constructed with respect to the hinge pin therefor as to avoid looseness of the parts and consequent rattling.

In the drawings:—Figure 1 is a vertical section of the upper part of the casing of an upright piano, showing the music desk and a hanger therefor embodying my invention. Fig. 2 is a generally similar fragmentary view showing the music desk swung upwardly to a position to expose the piano action in rear of the same. Fig. 3 is a fragmentary section, taken on line 3—3 of Fig. 1. Fig. 4 is a perspective view of one of the hangers. Fig. 5 is a view similar to Fig. 2, showing a slight modification of the hanger.

As shown in the drawings, A designates, as a whole, the upper portion of the casing of an upright piano, and B designates a swinging music desk of usual form which constitutes the front wall of said upper portion of the casing, it being swingingly mounted at its upper side in the casing so that it may be swung forwardly and upwardly to expose the piano action for inspection thereof, or to such angle as to afford an inclined music desk to support the music. Said music desk B is herein shown as supported between and mounted

on posts or pilasters A¹ constituting parts of the piano casing. The desk is supported from said posts or pilasters by hangers C which engage hinge pins or studs a fixed to the upper ends of said posts A¹. Two of said hangers and two pins or studs are employed, one pair located at each end of the upper side of the desk, in the usual manner. The said hangers each embraces a shank portion c by which it is attached to the rear face of the music desk, as by means of screws c¹ extending through apertures c² thereto. The hanger is formed at its other end to provide a hook or open loop, designated as a whole by c³. Said hook comprises two side members c⁴ c⁵ and is open at its lower end and closed at its upper end. It is adapted to hook over the hinge pin or stud a in a manner to swingingly and removably support the desk in the casing. The upper or closed end of said hook is formed with an outwardly offset portion c⁶ which provides on the inner face of the outer member c⁵ of the hook an oblique stop shoulder or surface c⁷ which engages the hinge pin or stud a in a manner to avoid the tendency of the music desk being pushed inwardly toward the piano action when the desk is swung to the position shown in Fig. 2 or to fall inwardly by gravity when swung upward beyond the horizontal.

The free end of the inner member c⁴ of the hook is curved away from the member c⁵, as indicated at c⁸, to provide a flaring receiving opening of the hook or loop, which facilitates the application of the hanger to the supporting pin or stud a.

In order that the hanger, as a whole, may be applied to the inner face of the music desk generally parallel with the plane of said inner face thereof, while avoiding the necessity of recessing the desk to receive the offset portion c⁶ of the hanger, the shank c is offset from the outer member c⁵ of the loop or hook to the plane of the offset portion c⁶; it being joined to said outer member by an offset portion c⁹, as indicated in Fig. 4.

It will thus be seen that the hangers C serve in the ordinary manner to swingingly support the music desk in the piano casing in a manner to permit it to be swung upwardly to the position shown in Fig. 2 or beyond such position, or to be swung forwardly at an angle to afford a music desk of the proper inclination, and that when said music desk occupies its upper or open posi-

tion the engagement of the shoulders c^7 with the pins serves to prevent the desk falling inwardly by gravity or being accidentally pushed inwardly into contact with the mechanism of the piano action, as would occur if the hanger loops or hooks be made straight throughout their length. The said hanger pins or studs a are herein shown as provided with heads a^1 having outwardly facing conical shoulders a^2 which are engaged by the edges of the hook members when the desk is mounted in position. This form of hanger stud or pin enables the music desk to be accurately adjusted laterally, or centered in the casing, while at the same time avoiding an undue binding or chafing of the hangers against said pins or studs, or the desk against the pilasters.

The spread of the hooks or loops c^3 may be made slightly narrower at the extremities of their closed ends than the diameter of the hinge pins or studs, as shown in Fig. 5, whereby each of said pins or studs finds its bearing at two points on the opposite sides of the hook instead of bearing against the inner curved face at the extreme end of the hook. An advantage of the arrangement shown is that it avoids looseness of fit between the hanger and pin and thereby prevents the parts rattling one on the other. If desired the bearing portion of the pins or studs may be covered by bushings made of cushioning material, such as felt, rubber and the like.

It is apparent that I have provided an exceedingly simple and effective hanger for the purpose described, having the advantages above set forth. Said hangers may advantageously be made of a single piece of bar or strap metal which is properly bent or shaped to produce the off-set hook or loop described, but may be otherwise constructed. The specific form of the hanger may be varied, however, so long as the stop is preserved at the hinged portion of the hanger which avoids tendency of inward shifting of the raised or open desk.

I claim as my invention:

1. The combination with the casing of an upright piano and the swinging music desk thereof, of hangers for swingingly supporting the music desk in the casing, combined with pins or studs in the casing detachably engaged by said hangers, said hangers being formed on their inner sides adjacent to the desk with interior stop surfaces or shoulders adapted for engagement by the said pins or studs when the desk is swung upwardly in a manner to avoid tendency of the desk being shifted rearwardly relatively to said pins or studs.

2. The combination with the casing of an upright piano and the swinging music desk thereof, of hangers for swingingly support-

ing said music desk in the casing, combined with pins in said casing detachably engaged by the hangers, said hangers comprising shank portions attached to the rear face of the music desk, and hooks engaging the pins which are open at their lower ends and closed at their upper ends, the upper or closed ends of said hooks being offset, for the purpose set forth.

3. The combination with the casing of an upright piano and the swinging music desk thereof, of hangers for swingingly supporting said music desk in the casing, combined with pins in said casing detachably engaged by the hangers, said hangers comprising shank portions attached to the rear face of the music desk, and hooks engaging the pins which are open at their lower ends and closed at their upper ends, the upper or closed ends of said hooks being forwardly offset to form interior shoulders for engagement with said pins, and the shanks of said hooks being offset to bring the same in the approximate plane of the offset portions of the hooks.

4. The combination with the casing of an upright piano and the swinging music desk thereof, of hangers for swingingly supporting said music desk in the casing, combined with pins in said casing detachably engaged by the hangers, said hangers comprising shank portions attached to the rear face of the music desk, and hooks, engaging the pins and open at their lower ends and closed at their upper ends, the spread of said hooks being of less width at their upper or closed ends than the diameter of the pins, whereby said pins engage with the inner faces of the side members only of the hooks below said closed ends, for the purpose set forth.

5. A hanger for music desks and the like comprising the shank c , the hook or loop portion c^3 having the offset portion c^6 to provide a stop surface or shoulder c^7 , as and for the purpose set forth.

6. The combination with the casing of an upright piano and the swinging music desk thereof, of hangers for swingingly supporting said music desk in the casing, combined with pins in said casing detachably engaged by the hangers, said hangers embracing elongated loops or hooks through which said pins extend, and the pins being provided at their inner ends with heads having outwardly facing conical shoulders adapted to engage the laterally inner sides of the hanger hooks or loops, for the purpose set forth.

In testimony, that I claim the foregoing as my invention I affix my signature in the presence of two witnesses, this 4th day of June A. D. 1908.

THEODORE H. LUNDE.
